US0D1049519S

(12) **United States Design Patent** (10) **Patent No.:** **US D1,049,519 S**
(45) **Date of Patent:** **** Oct. 29, 2024**

(54) **DOG TRAINING COLLAR SET**

(71) Applicant: **Shenzhen Nurbenn Technology Co., Ltd.**, Guandong (CN)

(72) Inventor: **Zhimin Ying**, Guandong (CN)

(73) Assignee: **Shenzhen Nurbenn Technology Co., Ltd.**, Guandong (CN)

(**) Term: **15 Years**

(21) Appl. No.: **29/863,938**

(22) Filed: **Dec. 23, 2022**

(51) LOC (14) Cl. **30-99**

(52) U.S. Cl.

USPC **D30/199**

(58) **Field of Classification Search**

USPC D10/78, 80, 104.1; D13/168, 154; D14/137, 217, 218; D30/144, 151, 152, D30/160, 199

(57) **CLAIM**

The ornamental design for a dog training collar set as shown and described.

DESCRIPTION

FIG. 1 is a front, right, and top perspective view of a dog training collar set, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed lines in the drawings depict portions of the dog training collar set that form no part of the claimed design.

1 Claim, 8 Drawing Sheets
